UNITED STATES PATENT OFFICE.

ELIZABETH E. HOWELL, OF DENVER, COLORADO.

AUTOMOBILE.

1,171,438.

Specification of Letters Patent. Patented Feb. 15, 1916.

Application filed August 19, 1914. Serial No. 557,579.

To all whom it may concern:

Be it known that I, ELIZABETH E. HOWELL, a citizen of the United States, residing at Denver, in the county of Denver and State of Colorado, have invented certain new and useful Improvements in Automobiles, of which the following is a specification.

My invention relates to improvements in automobiles and its object resides in providing coöperative means by which the seats of a motor vehicle may by a simple adjustment, be converted into a couch for supporting one or more persons in a recumbent position.

15 My invention is designed to provide either a single or a double couch without any alteration in the construction or position of the parts of the automobile, other than an adjustment of the back of its front seat, and it thus adapts the vehicle for use as a bed during extensive journeys, or as an ambulance in case of accident or sudden illness.

An embodiment of my invention is illustrated in the accompanying drawings in the 25 various views of which like parts are similarly designated, and in which, —

Figure 1 is a plan view of an automobile to which my invention has been applied, Fig. 2, a sectional elevation of the same, 30 Fig. 3, an enlarged fragmentary section of the body-portion of the vehicle showing the parts in their coöperative position for the provision of a couch, Fig. 4, an enlarged fragmentary section along the line 4—4, Fig. 1, showing one of the devices provided for maintaining the adjustable back of the front seat of the machine in its normal position, and Fig. 5, a perspective view of the 35 end of the arm which divides the front seat of the machine into two seating spaces, and which secures the members of the back of the same in their normal position.

The motor vehicle shown in the drawings has a rear seat 2 at the end of its tonneau, 45 and a front seat 3, the back 4 of which is divided into two parts connected with the seat by hinges which permit of their being separately lowered to a position in horizontal alinement with the same.

50 The seat 3 is divided into two seating spaces by means of a curved arm 5 which at one of its ends is pivotally secured at the front of the seat as at 6, and which at its opposite end has two downwardly extend-

ing pins 7 for insertion into corresponding eyes or sockets 17 formed on the members of the back adjacent their adjoining edges.

In addition to the curved arm which by the means above described, holds the members of the back of the seat in their normal 60 position, I provide spring catches 8 which are operatively mounted in openings in the sides of the car-body to normally project into sockets formed in the outer edges of the members, as best shown in Fig. 4 of the 65 drawings.

The members of the back 4 have at their respective rear sides, sockets 9 which are preferably formed in the fastening members of the hand rails 10, to receive the angular 70 ends 12 of supporting legs 13 which in practice are at their lower extremities inserted into openings 14 in the floor of the car body.

The legs are provided above their end portions which occupy the openings 14, with 75 integral feet formed by concentric flanges 15 which by engagement with the floor of the car limit their downward movement, and aid in providing a stable and rigid support for the respective member of the back after 80 it has been lowered to the position shown in Fig. 3 of the drawings.

When the height of the back of the front seat corresponds with the distance between the front and back seats of the vehicle as in 85 the form shown in Fig. 3, its members will in their lowered position, provide in conjunction with said seats and without the aid of other parts, a couch adapted to support a body in a recumbent position. If, however, 90 the distance between the seats exceeds the height of the back 4 of the front seat, an adjustable contrivance is provided to span the space between the front edge of the back seat and the edges of the members of the 95 back when they are adjusted to their position in a plane with the seats.

In the form of my invention shown in Figs. 1 and 2 of the drawings, this form consists of a pair of boards or shelves 16 which are slidably mounted underneath the rear seat of the vehicle to be moved forwardly in adjacency to the edges of the respective members as is shown in the drawings.

When the automobile is in ordinary use, 105 the curved arms 5 and the spring catch 8 co-operate to maintain the members of the back of its front seat rigidly in an upright posi-

tion, the sliding shelves 16 are concealed beneath the rear seat 2 and the removable legs 13 are stored in a convenient place of the vehicle.

5 To convert the seats into a couch for one person, either of the members which conjointly compose the back of the front seat, is moved about its hinges until it is level with both the front and rear seats and it is in this 10 position supported upon the floor of the car by means of the legs which are attached in the manner hereinbefore explained:

If the height of the back is insufficient to span the entire space between the seats, the 15 corresponding shelf is moved outwardly until the space between the edge of the back and the front edge of the rear seat is closed.

To provide a double couch, both members of the back are adjusted in the manner explained and it will thus be seen that by the use of my invention, a single couch may be readily formed at either side of the vehicle, in which case the arm 5 maintains the upright member of the back in its normal position, and at the same time divides the corresponding seat from the couch, or that the entire body of the vehicle may be converted into a double couch when the arm 5 is turned out of the way, by moving it about its pivot.

20 30 It will be understood that the means for fastening and supporting the members of the back as shown and described, may be varied in construction and in their relative.

arrangement, within the spirit of my invention as set forth in the following claims: 35

1. A motor-vehicle having a rear-seat and a front-seat, rearward of the latter an adjustable back which is hinged to be lowered to a position in a plane with said seats, and which has at its rear side a hand-rail and in 40 the fastening thereof, a normally vacant socket for the attachment of a removable leg, means for maintaining said back in its normal position, and a leg having a part adapted to be removably inserted in said socket, 45 and a foot to engage the floor of the vehicle.

2. A motor-vehicle having a rear-seat, a front-seat, rearward of the latter a back composed of two adjustable members which 50 are hinged to be lowered to a position in a plane with said seats, and a device having means coöperating with correlative parts on said members for maintaining them in their normal position, the said device extending above the plane of the front seat whereby to divide the same into two seating spaces, and to provide an arm rest for an occupant of the seat. 55

In testimony whereof I have affixed my 60 signature in presence of two witnesses.

ELIZABETH E. HOWELL.
